TRANSMITTER CIRCUIT ARRANGEMENT

Wilhelm Kummerer, Berlin, Germany, assignor to
Telefunken Gesellschaft für Drahtlose Tele-
graphie m. b. H., Berlin, Germany, a corpora-
tion of Germany

Application December 17, 1932, Serial No. 647,721
In Germany December 29, 1931

8 Claims. (Cl. 179—171)

The increasingly severer conditions of modern amplifier and transmitter construction as regards the avoidance of non-linear distortion necessitate the adoption of special arrangements and schemes. The present invention relates to amplifiers which include counter-coupling or compensating coupler schemes.

The novel features of the invention have been pointed out with particularity in the claims attached hereto.

The invention, however, as to nature and operation, will be described in detail. In such description reference will be made to the drawings, in which:

15 Figures 1 and 2 show tube characteristics which aid in the disclosure of the invention; while,

20 Figures 3 to 7 inclusive show different modifications of an amplifier constructed in accordance with my invention.

Referring to the drawings, Figure 1 shows a tube characteristic, the lower end of which is idealized as to form. The tube shall be supposed to work as an amplifier of the class B type, for instance, exactly at the bottom knee, that is, at the lower end of the straight line portion of the curve. The fundamental harmonic of the ensuing alternating current, upon application of a sinuous alternating grid potential, will then be 25 proportional to the latter as long as the tube is operating in the rectilinear part of its characteristic curve. The assumption shall be made that the active grid potential is composed of the difference of a potential which is linearly variable with respect to the signalling wave or current to be amplified and an oppositely acting potential of lower absolute value which is proportional to the amplified current of fundamental frequency or a harmonic thereof. Now, as long 30 as the resultant potential stays in the rectilinear part of the characteristic, the impressed and the oppositely coupled potential will always be proportional to each other, in other words, the generated current increases linearly with increase 35 in the amplification of the applied potential, though at a less rapid rate than is true in the absence of counter coupling. But as soon as the resultant voltage comes to be within the lower portion of the upper knee of the characteristic 40 45 50 the applied current no longer will increase linearly, hence, also the counter potential will decrease or increase less rapidly with the consequence that the resultant alternating grid voltage grows faster than linearly. Hence, the tube will be excited somewhat more than in the case

where the counter coupling is absent; the ensuing current therefore is larger, and the shape of the current comes closer to a linear condition than is true in the absence of counter coupling. This consideration, as will be understood, holds, of course, true also of the reversed behavior in the lower knee and also for amplitude-dependent external resistance (for instance, grid circuits for which the damping is variable as a result of non-linearity of the grid direct current). 10 In graphic form the resulting improvement can be clearly represented in the following manner: Plate current and impressed grid alternating voltage, in the absence of counter coupling, shall be denoted by i and e_g , in the presence of counter-coupling by i' and e_g' . Suppose the counter-coupling is

$$e_{ geg } = k \cdot i'$$

then without counter-coupling

$$i = Se_g$$

and with counter-coupling

$$i' = S(e_g' - e_{ geg }) = Se_g' - Sk i'$$

25 Examining the case of like resultant plate current, when $i = i'$ then:

$$Se_g = Se_g' - Sk i'$$

or

$$e_g' = e_g + k i;$$

in other words, the grid alternating potential e_g' to be impressed upon the tube in the case of counter-coupling is equal to the original grid potential e_g increased by the addition $k i$. Ex- 35 pressed in graphical form this means nothing else than the shearing in an amount equal to the straight

$$\frac{e_{ geg }}{k}$$

40 In other words, the characteristic curve is shifted and straightened out as shown in Figure 1 at $i' = f(e_g')$. Now, it will be readily understood that the current curve for e_g' should be less curved than in the case of e_g seeing that in the curved portion the value of e_g , which no longer varies linearly with linearly growing current, is joined merely additively to the straight

$$\frac{e_{ geg }}{k}$$

45 50 55 In other words, contrary to what might be thought at first blush, the process does not involve a mere change in scale.

In order to make the resulting improvement still more conspicuous the current-curves obtained are plotted in Figure 2 with changes in scale of e_g in such a way that beginning and end 5 coincide.

The advantages as regards properties of modulation, at least in the case of radio frequency arrangements, can be effectively realized only provided that in spite of the potential of the main 10 circuit brought to the grid, neutralization is maintained. This requirement fundamentally is fulfilled by the simple bridge scheme in a capacitive grid neutralized arrangement as shown in Figure 3. It can be seen from the illustration quite 15 readily that the plate potential by way of the internal tube capacity between grid and plate and the resultant grid cathode capacity is divided by condensers NC and AC. Plate potential is impressed with the same phase, i. e., in counter- 20 coupling sense, upon the grid at point B by NC and on the other terminal of 2 by AC. The other point of connection, A, of the inductance 2, on which the oscillations from the pilot valve are impressed by 1, looked at from the viewpoint of 25 the master transmitter, owing to the voltage division by way of the neutralizing condenser NC and the other grid voltage divider condenser AC, receives the same voltage as the grid point B; in other words, no electromotive force of the master 30 valve oscillation circuit 4, 5 will produce a current in the grid coupling coil, and the arrangement therefore is neutralized. Since, at least for longer waves, voltage division by way of the internal tube capacity, because of the rotation of the grid 35 phase by the active grid current, may not be expected to conduce to satisfactory results, the internal tube capacity, according to the invention, between grid and plate is raised by supplementary capacities. In fact, in the limiting case, 40 conditions in this respect may be pushed to a point where the entire capacity of the oscillation circuit is placed in the resultant grid plate or neutralizing capacity as indicated in Figure 4, wherein the capacity 5 has been omitted. This 45 arrangement is otherwise the same as Figure 3.

Generally speaking, an inductive type of counter-coupling may be preferable to the capacity-type where long waves are dealt with. A grid neutralizing scheme comprising an inductive 50 counter-coupling is shown in Figure 5, in which the potential producing the counter-coupling effect is applied to bridge points in reference to the pilot transmitter by way of winding 7 and impedances 2 as well as capacities AC and NC so 55 that neutralization is not disturbed.

In a similar manner also amplifiers with plate neutralization can be provided with the counter-coupling scheme without impairing neutralization. A number of exemplified embodiments are 60 shown in Figures 6 and 7. Here the capacity NC neutralizes the grid to plate capacity of the tube only. The additional driving effect is obtained by coupling winding 4 by way of windings 65 7 and 9 to the winding 10 connected to the divided input winding 2 in such a manner that the anode circuit 4, 5 impresses no disturbing voltages on the pilot oscillator by way of winding 2. In the latter two instances, in order to restore the state 70 of freedom from reaction impaired by the counter-coupling, a condenser C_G must be inserted, and this condenser, for instance, in the presence of a voltage divider ratio of 1:1 at the grid coupling coil must be equal to the resultant grid-fil- 75

ament by resultant grid-filament capacity is the capacity between grid and filament existent from the viewpoint of the pilot valve; in other words, firstly, the grid-filament capacity itself, and parallel thereto the series arrangement comprising the grid-plate capacity and upper voltage divider and the series arrangement comprising the neutralizing capacity and the lower voltage divider. 5

Having thus described my invention and the operation thereof, what I claim is: 10

1. Means for amplifying alternating currents comprising, a thermionic tube having a control grid, an anode and a cathode, an alternating current circuit connected between said control grid and said cathode, which circuit includes an inductance which may be energized by the currents to be amplified, an alternating current circuit connected between said anode and said cathode, said last named circuit being tuned by capacity to the frequency of the alternating currents to be amplified, a circuit for impressing potentials from said anode circuit to the control electrode of said tube, said circuit simultaneously impressing said potentials on the terminal of the inductance in said control electrode cathode circuit connected with said control electrode to offset potentials transferred through the impedance of said tube from said anode to said control electrode, and means for compensating the effect of said potentials applied from said output circuit to 30 said control electrode and inductance terminal on the alternating current flowing in said inductance including a circuit for transferring potentials from said output circuit to the other terminal of said inductance. 35

2. An arrangement as recited in claim 1 in which the potentials applied from the output circuit to the control grid and simultaneously to the terminal of the inductance connected therewith are in phase with the potentials applied 40 from the output circuit to the other terminal of said inductance.

3. An arrangement as recited in claim 1 in which the circuit for transferring potentials from the output circuit of said thermionic tube to the control grid and simultaneously to the terminal of the inductance in the input circuit connected with said control grid includes a variable capacity, and the circuit for transferring alternating current potentials from the anode and output circuit of said tube to the other terminal of said inductance in said control grid cathode circuit includes a variable capacity. 45

4. Signalling means comprising, a source of alternating current potentials, a thermionic tube, 55 said tube having an anode, a cathode and a control electrode, an inductance connected between said control electrode and said cathode, said inductance being coupled to said source of alternating current, an output circuit connected between 60 said anode and said cathode, said output circuit being tuned by the capacity of said tube to the frequency of the alternating current source, means for preventing harmonic distortion in said circuit comprising, a circuit connected between 65 the anode of said tube and the control grid of said tube to transfer potentials from the anode of said tube to the control grid of said tube, and means for preventing the potentials transferred from said anode to said control grid from reacting 70 through said inductance connected with said control grid on said source comprising, a circuit connected between the anode of said tube and the terminal of said inductance remote from said control grid. 75

5. An arrangement as claimed in claim 4 in which said circuit connected between said anode and said control grid and said circuit connected between said anode and the terminal of said inductance remote from said control grid both include variable capacities.

6. Amplifying means comprising, a thermionic tube having an anode, a cathode and a control grid, an inductance adapted to be energized by frequencies to be amplified, a connection between a point on said inductance and the control grid of said tube, a connection between another point on said inductance and the cathode of said tube, a variable capacity connecting the anode of said tube to the cathode of said tube, a second inductance, a connection between a point on said second inductance and the cathode of said tube, a connection between the anode of said tube and one terminal of said last named inductance, a variable capacity connecting a point on said last named inductance to a point on said first named inductance, a neutralizing capacity connected between the anode and control grid of said tube, and means for coupling the first named inductance to the second named inductance.

7. A source of alternating current potentials and means for amplifying the potentials from said source comprising, a thermionic tube having an anode, a cathode and a control grid, an inductance connected between said control grid and said cathode, said inductance being coupled

to said source, a capacity connecting each terminal of said inductance to the anode of said tube, a second inductance connected between the anode and cathode of said tube, impedances connected with terminals of said first named inductance, and an additional inductance connecting said impedances to the cathode of said tube, said additional inductance being coupled to said second named inductance.

8. Amplifying means comprising, a thermionic tube having anode, cathode and control grid electrodes, an inductance adapted to be energized by alternating current potentials to be amplified, a connection between one terminal of said inductance and the control grid of said tube, a connection between a point on said inductance and the cathode of said tube, said last named connection including a second inductance, a third inductance, said third inductance being coupled to said second named inductance, a connection between a point on said third inductance and the cathode of said tube, a connection between one terminal of said third inductance and the anode of said tube, said terminal also being connected to the control grid of said tube by way of a variable capacity, and a connection between the other terminal of said third named inductance and the control grid of said tube, said last named connection also including a variable capacity.
